PACKER ANCHOR

Walter L. Church, Houston, Tex.

Application April 22, 1943, Serial No. 484,105

7 Claims. (Cl. 166—12)

1

This invention relates to a packer for wells and has particular relation to an expandible packer designed for forming a seal between the well tubing and an outer well pipe or casing, with means for anchoring the packer against upward movement in the well casing.

Another object is to provide a packer assembly so connected to the tubing that the tubing may be readily detached and withdrawn.

In completing a well a packer is set between the tubing and casing. It is sometimes set between two producing strata and production from the lower stratum is carried to the ground surface through the tubing while production from the upper stratum is carried to the ground surface through the casing. The packer should be anchored against upward movement or downward movement as otherwise it might be moved in the one direction or the other on account of unequal pressures on opposite sides of it. If the packer is not anchored against upward movement and the well pressure beneath it exceeds that above it, it is liable to be moved upwardly with sufficient force to bend or "corkscrew" the tubing so that the tubing will be injured or rendered completely worthless for further use when withdrawn. It is an object of the present invention to provide means for securely anchoring the packer against movement in either direction when it is once set in a well.

The invention herein disclosed embodies also novel means for setting and anchoring the packer which constitutes an improvement over that type of assembly disclosed in my application, filed December 2, 1940, under Serial Number 368,127, which issued on February 27, 1944, under Patent No. 2,352,433.

With the above and other objects in view the invention has particular relation to certain novel features of construction, operation and arrangement of parts, an example of which is given in this specification and illustrated in the accompanying drawings, wherein:

Figure 1 shows an elevational view of the complete assembly showing the packer expanded, or set.

Figures 2 and 3 show side views, partly in section, of the upper and lower ends of the assembly showing the packer collapsed.

Figure 4 shows a cross-sectional view taken on the line 4—4 of Figure 3.

Figures 5 and 6 show side views partly in section, of the upper and lower ends respectively, of the assembly showing the packer expanded or set, and

2

Figure 7 shows a cross-sectional view taken on the line 7—7 of Figure 6.

Referring to the drawings the numeral 1 designates the well tubing which extends to the ground surface and the numeral 2 designates the outer well pipe, or casing which also extends to the ground surface. On the tubing there is a tubular cage 3 having an inside downwardly tapering seat 4 at its lower end whereon there is mounted an expandible downwardly tapering slip 5. This slip has, on the inside, upwardly pitched, right-hand teeth or threads 6 and screwed onto the lower end of the tubing 1 there is a coupling 7 whose upper end has external downwardly pitched right hand threads 8 engageable with the teeth of the said slip. Mounted in the cage 3 are the friction members 9 which are retained against detachment by the end stops 10, 10 and which are held yieldingly in their outer position by the pressure springs 10a so that they will be held in frictional contact with the well casing 2 as shown in Figures 1 to 6. The springs 10a are seated in a bushing 3a driven into the cage 3. When the tubing is turned to the right the threads 8 will be disengaged from the threads 6 and the tubing can be moved downwardly. In order to re-engage said threads the tubing may be given a straight pull upwardly and the threads 8 will ratchet past the threads 6 and reengage therewith, the slip 5 being made expandible to permit this.

The coupling 7 and the opposing end of cage 3 have interengaging stops 11 and 12 respectively to prevent the threads 8 from becoming too tightly screwed into the threads 6 upon a relative reverse rotation of these parts.

Mounted for radial movement in the cage 3 there are casing engaging jaws 13 whose inner sides converge downwardly and whose outer sides are formed with downwardly pitched teeth. These jaws are normally maintained in their inner position out of engagement with the casing by the flat springs 14 whose lower ends are fastened to the cage and whose upper ends are free and located in vertical outside grooves in the jaws. The upper ends of the jaws are limited in their outward movement by the stops 15 on the cage at the upper ends of the jaws.

There is a downwardly tapering jaw expander 16 within the jaws 13 and the upper end of the cage 3 extends above the said jaws and has an inside key 17 engageable with an external shoulder 18 on said expander to prevent detachment of the cage from the expander.

Screwthreaded onto the upper end of the jaw

expander 16 is a sleeve 19 and screwthreaded into the upper end of the sleeve is an annular abutment 20.

Slidably mounted within this abutment and extending above it is a tubular packer support 21 whose lower end has an outside annular shoulder 22 underneath and engageable with the lower end of the abutment 20 and whose upper end is screwthreaded into a set collar 24, above. Surrounding the packer support is a suitable sleeve-like expandable packer 23, which is formed of rubber or other suitable expandable material so as to form, when expanded, a fluid tight seal with the outer well pipe or casing 2. The packer, at its lower and upper ends, is fitted into the adjacent ends of the annular abutment 20 and set collar 24 respectively as shown in Figures 2 and 3.

An upper tubular cage 25 has its lower end screwthreaded onto the upper end of the set collar. Mounted for radial movement in the upper end portion of the cage 25 are casing engaging jaws 26 whose inner sides are inclined downwardly and inwardly and whose outer sides are formed with upwardly pitched teeth. These jaws are normally held in their inner position by the flat springs 27 whose lower ends are fastened to the cage 25 and whose upper ends are free and fit in vertical slots in the jaws 26. The upper ends of the jaws are limited in their outward movement by stops 28 on the cage 25.

Within the jaws 26 there is an expander 29 whose outer surface tapers downwardly. This expander is initially fastened to the upper end of the cage 25 by a shearable pin 30.

On the tubing 1 above the expander 29 there is an enlarged coupling 31 and on the tubing 1 beneath the expander 29 and spaced the required distance beneath the coupling 31 there is an enlarged collar 32.

Clamped in an internal recess in the set collar 24 by the gland 33 is a stuffing box 34 which closely surrounds the tubing 1.

There is a release sleeve 35 positioned within packer support 21 and spaced therefrom and whose upper end is screwthreaded into the set collar 24. The release sleeve closely surrounds the tubing 1 and extends downwardly through the sleeves 21 and 19 and on down through the lower cage 3 and bushing 3a therein.

In use the apparatus is assembled as shown in Figures 2 and 3 with the upper end of the coupling 7 engaged and held by the slip 5, and with the expander 29 pinned to the upper end of cage 25. While being so lowered the expander 16 will be held in its upper position by the sleeve 35 whose lower end rests on the upper end of the coupling 7 as shown in Figure 3 and the packer 23 will be collapsed. When the selected level has been reached to set the packer the tubing may be turned to the right. The cage 3 will be held stationary by the friction members 9 and the coupling 7 will be screwed out of the slip 5. Thereupon the tubing may be lowered and the coupling 31 will land on the expander 29 causing the cage 25 and set collar 24 to move downwardly thus forcing the sleeve 19 and the expander 16 downwardly and the jaws 13 will be expanded, or moved outwardly into engagement with the casing 2 thus anchoring the assembly against further downward movement, as a whole. As the tubing is moved further downwardly the cage 25 and set collar will also be moved downwardly to cause the expansion of the packer 23 into sealing relationship with the casing 2 as shown in Figure 1. Upon further downward movement of

the tubing 1, its weight will cause the pin 30 to be sheared and the jaws 26 will be expanded into engagement with the casing 2 and the packer will be thus maintained expanded and also anchored against upward movement in case high pressure should develop beneath the packer.

Depending from the coupling 7 there is an extension tube 1a which forms, in effect, a continuation of the tubing 1 and which may extend any selected distance down into the well.

The tubing 1 is provided with a plurality of slots 36 which will be located beneath the stuffing box 34 when the packer is set and production is being carried on through the tubing, as shown in Figure 5 but which will be located above said stuffing box, as shown in Figure 2 when the assembly is being moved in the well. It is to be understood that the well is filled with fluid and while lowering or withdrawing or adjusting the assembly in the well, it is desirable that circulation be maintained from within the tubing to the outside of the tubing and vice versa so that the pressure will be equalized thus relieving the packer assembly from a major portion of the weight of the liquid column above during these movements. This circulation may be maintained through the slots 36 and the surrounding holes 37, through the cage 25, when the assembly is in the position shown in Figure 2.

With the packer set, as shown in Figure 1, production may be carried on through the tubing 1 to the ground surface.

As illustrated in Figures 1 and 5 the casing 2 may be provided with perforations 38, above the packer and opposite a producing stratum so that gas or oil may be also produced and delivered to the ground surface up through the casing around the tubing.

When it is desired to do so the assembly, under normal conditions, may be removed from the well. In order to do this the tubing may be pulled upwardly thus pulling the upper end of the coupling 7 up into the slip 5, the threads 8 of the coupling ratcheting past the threads 6 of the slip so that said threads may be inter-engaged by a direct upward movement of the tubing. Upon such upward movement the coupling 32 will engage the lower end of, and elevate, the expander 29 and the springs 27 will release the jaws 26 from the casing 2. At the same time the upper end of the coupling 7 will engage the lower end of the sleeve 35 forcing it and the set collar 24 upwardly which will cause an upward movement of the packer support 21. The external shoulder 22 of this support will engage the lower end of the abutment 20 thus elevating said abutment and the sleeve 19 and expander 16 to release the jaws 13 and the springs 14 will then disengage said jaws from the casing 2 and the entire assembly may be pulled from the well.

It sometimes happens that the packer assembly becomes stuck and cannot be released. In such case the tubing 1 may be unscrewed and parted at the coupling 31. For this purpose this coupling 31 may be of the safety joint type of any conventional construction to facilitate the parting of the tubing so that the tubing may be withdrawn and saved.

The upper end of the jacket, or release sleeve, 35 is provided with a vertically elongated slot 39 and a key 40 is attached to the tubing and works in said slot whereby the tubing and release sleeve are caused to rotate together but are allowed a limited, relative, longitudinal movement.

What I claim is:

1. A device for forming a seal between an inner tubing and the walls of the well, and which includes an expansible sleeve-like packer with means beneath the packer for supporting the packer; a tubular upper cage above the packer around the inner tubing, radially movable wall engaging slips mounted in the cage, a downwardly tapering expander, a shearable pin securing the expander in the cage above the slips, an external 5 projection on the tubing above the expander and engageable with the expander to move the cage downwardly to subject the packer to endwise compressive force to expand the packer, said pin being thereafter shearable by the weight of the inner tubing and the expander being thereupon movable downwardly between said slips to expand the slips into engagement with the walls of the well to maintain the packer expanded, and an external 10 projection on the tubing engageable with the expander upon subsequent upward movement of the tubing to release the expander from the slips, means for retracting the slips upon such release to disengage them from the walls of the well to allow the packer to collapse and be withdrawn from the well.

2. A device for packing wells and shaped to surround an inner tubing and comprising an upper tubular cage, a downwardly tapering, upper, slip expander secured within the cage, casing engaging slips in the cage around the expander, releasable means initially retaining the expander in inactive position, yieldable means normally retaining said slips retracted or in their inner position, a set collar connected to the lower end of the cage, a packer support depending from the set collar, a sleeve-like expansible packer beneath the set collar around said support, a sleeve around said packer support whose upper end has an abutment against the lower end of the packer, a lower 15 downwardly tapering slip-expander carried by the lower end of said sleeve, a lower tubular cage, casing engaging slips in said lower cage around said lower expander, yieldable means normally holding the slips in the lower cage retracted, a coupling on said inner tubing releasably connected to the lower cage, a coupling on the inner tubing above the upper expander arranged to engage the upper expander and move the upper cage, the set collar, the packer and the lower expander downwardly, upon release of the inner tubing from the lower cage and the downward movement of the inner tubing, whereby the lower slips will be expanded by the lower expander and caused to engage the casing to support the packer and to cause expansion of the packer upon further downward movement of the inner tubing, said upper expander being releasable and downwardly movable by the weight of the tubing to expand the upper slips into engagement with the casing, and an external abutment on the inner tubing engageable with the upper expander, upon subsequent upward movement of the tubing and effective to release said upper expander from the upper slips.

3. A device for packing wells and shaped to surround an inner tubing and comprising an upper tubular cage, a downwardly tapering, upper, slip expander within the cage, a shear pin securing said expander to the cage, casing engaging slips in the cage around the expander, said shear pin initially retaining the expander in inactive position, yieldable means normally retaining said slips retracted or in their inner position, a set collar connected to the lower end of

the cage, a packer support depending from the set collar, a sleeve-like expansible packer beneath the set collar around said support, a sleeve around said packer support whose upper end has an abutment against the lower end of the packer, a lower downwardly tapering slip-expander carried by the lower end of said sleeve, a lower tubular cage, casing engaging slips in said lower cage around said lower expander, yieldable means normally holding the slips in the lower cage retracted, a coupling on said inner tubing releasably connected to the lower cage, a release sleeve arranged to rest on said coupling and connected to and supporting the set collar while going into a well to maintain the packer collapsed, a coupling on the inner tubing above the upper expander arranged to engage the upper expander and move the upper cage, the set collar, the packer and the lower expander downwardly, upon release on the inner tubing from the lower cage and the downward movement of the inner tubing, whereby the lower slips will be expanded by the lower expander and caused to engage the casing to support the packer and to cause expansion of the packer upon further downward movement of the inner tubing, said pin being shearable and said upper expander being releasable and downwardly movable by the weight of the tubing to expand the upper slips into engagement with the casing.

4. A device for packing wells and shaped to surround an inner tubing and comprising an upper tubular cage, a downwardly tapering, upper, slip expander releasably secured within the cage, casing engaging slips in the cage around the expander, releasable means initially retaining the expander in inactive position, yieldable means normally retaining said slips retracted or in their inner position, a set collar connected to the lower end of the cage, a seal within the set collar adapted to surround said inner tubing, a packer support depending from the set collar, a sleeve-like expansible packer beneath the set collar around said support, a sleeve around said packer support whose upper end has an abutment against the lower end of the packer, a lower downwardly tapering slip-expander carried by the lower end of said sleeve, a lower tubular cage, casing engaging slips in said lower cage around said lower expander, yieldable means normally holding the slips in the lower cage retracted, a coupling on said inner tubing releasably connected to the lower cage, a collar on said inner tubing engageable with the lower end of the upper expander upon upward movement of the inner tubing, a coupling on the inner tubing above the upper expander arranged to engage the upper expander and move the upper cage, the set collar, the packer and the lower expander downwardly, upon release of the inner tubing from the lower cage and the downward movement of the inner tubing, whereby the lower slips will be expanded by the lower expander and caused to engage the casing to support the packer and to cause expansion of the packer upon further downward movement of the inner tubing, said upper expander being releasable and downwardly movable by the weight of the tubing to expand the upper slips into engagement with the casing.

5. A device for packing wells and shaped to surround an inner tubing and comprising an upper tubular cage, a downwardly tapering, upper, slip expander secured within the cage, casing engaging slips in the cage around the expander, re-

leasable means initially retaining the expander in inactive position, yieldable means normally retaining said slips retracted or in their inner position, a set collar connected to the lower end of the cage, a packer support depending from the set collar, a sleeve-like expansible packer beneath the set collar around said support, a sleeve around said packer support whose upper end has an abutment against the lower end of the packer, a lower downwardly tapering slip-expander carried by the lower end of said sleeve, a lower tubular cage, means on the lower cage in frictional engagement with the well casing, casing engaging slips in said lower cage around said lower expander, yieldable means normally holding the slips in the lower cage retracted, a coupling on said inner tubing releasably connected to the lower cage, a coupling on the inner tubing above the upper expander arranged to engage the upper expander and move the upper cage, the set collar, the packer and the lower expander downwardly, upon release of the inner tubing from the lower cage and the downward movement of the inner tubing, whereby the lower slips will be expanded by the lower expander and caused to engage the casing to support the packer and to cause expansion of the packer upon further downward movement of the inner tubing, said upper expander being releasable and downwardly movable by the weight of the tubing to expand the upper slips into engagement with the casing and an external projection on the tubing engageable with the upper expander to release it from the upper slips upon subsequent upward movement of the tubing.

6. A device of the character described comprising, an upper tubular cage, a downwardly tapering upper, slip expander within the cage, casing engaging slips in the cage around the expander, releasable means initially retaining the expander in inactive position, yieldable means normally retaining said slips retracted or in their inner position, a set collar connected to the lower end of the cage, a packer support depending from the set collar, a sleeve-like expansible packer beneath the set collar around said support, a sleeve around said packer support whose upper end has an abutment against the lower end of the packer, a lower downwardly tapering slip-expander carried by the lower end of said sleeve, a lower tubular cage, casing engaging slips in said lower cage around said lower expander, yieldable means normally holding the slips in the lower cage retracted, an inner tubing extending through said cages and seal, a coupling on said inner tubing releasably connected to the lower cage, an upwardly facing shoulder on said inner tubing engageable with the lower end of the upper expander upon upward movement of the tubing, a downwardly facing shoulder on the inner tubing above the upper expander arranged to engage the upper expander and move the upper cage, the set collar, the packer and the lower expander downwardly, upon release of the inner tubing from the lower cage and the downward movement of the inner tubing, whereby the lower slips will be expanded by the lower expander and caused to engage the casing to support the packer and to cause expansion of the packer upon further downward movement of the inner tubing, said upper expander being releasable and downwardly movable by the weight of the tubing to expand the upper slips into engagement with the casing, said inner tubing having perforations which are above said seal when the tubing is in its upper position but which are below said seal when the tubing is moved downwardly to set the packer.

arranged to engage the upper expander and move the upper cage, the set collar, the packer and the lower expander downwardly, upon release of the inner tubing from the lower cage and the downward movement of the inner tubing, whereby the lower slips will be expanded by the lower expander and caused to engage the casing to support the packer and to cause expansion of the packer upon further downward movement of the inner tubing, said upper expander being releasable and downwardly movable by the weight of the tubing to expand the upper slips into engagement with the casing, said upwardly facing shoulder being provided to release the upper expander from the corresponding slips to permit release of said slips from the well casing.

7. A device of the character described comprising, an upper tubular perforated cage, a downwardly tapering upper, slip expander within the cage, casing engaging slips in the cage around the expander, releasable means initially retaining the expander in inactive position, yieldable means normally retaining said slips retracted or in their inner position, a set collar connected to the lower end of the cage, a seal within the set collar adapted to seal around an inner tubing, a packer support depending from the set collar, a sleeve-like expansible packer beneath the set collar around said support, a sleeve around said packer support whose upper end has an abutment against the lower end of the packer, a lower downwardly tapering slip-expander carried by the lower end of said sleeve, a lower tubular cage, casing engaging slips in said lower cage around said lower expander, yieldable means normally holding the slips in the lower cage retracted, an inner tubing extending through said cages and seal, a coupling on said inner tubing releasably connected to the lower cage, an upwardly facing shoulder on said inner tubing engageable with the lower end of the upper expander upon upward movement of the tubing, a downwardly facing shoulder on the inner tubing above the upper expander arranged to engage the upper expander and move the upper cage, the set collar, the packer and the lower expander downwardly, upon release of the inner tubing from the lower cage and the downward movement of the inner tubing, whereby the lower slips will be expanded by the lower expander and caused to engage the casing to support the packer and to cause expansion of the packer upon further downward movement of the inner tubing, said upper expander being releasable and downwardly movable by the weight of the tubing to expand the upper slips into engagement with the casing, said inner tubing having perforations which are above said seal when the tubing is in its upper position but which are below said seal when the tubing is moved downwardly to set the packer.

WALTER L. CHURCH.
